CLAIM

The ornamental design for a louver, as shown and described.

DESCRIPTION

FIG. 1 is a perspective view of a louver, showing the new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

The broken lines shown in FIGS. 1, 6 & 7 depict portions of the louver that form no part of the claimed design.

1 Claim, 3 Drawing Sheets(56)
